CLAIM

The ornamental design for a magnetized thimble, as shown and described.

DESCRIPTION

FIG. 1 is a perspective view of a magnetized thimble showing my new design;
FIG. 2 is a bottom plan view thereof;
FIG. 3 is a front elevational view thereof, the rear view being a mirror image of that shown; and
FIG. 4 is a top plan view thereof.

FIG. 2

FIG. 1

FIG. 3

FIG. 4
